UNITED STATES PATENT OFFICE.

EDWARD A. RUSSELL, OF CHICAGO, ILLINOIS, ASSIGNOR TO VAPOR CAR HEATING COMPANY, INC., OF CHICAGO, ILLINOIS, A CORPORATION OF NEW YORK.

AUTOMATIC CAR-HEATING SYSTEM.

Application filed May 1, 1922, Serial No. 557,551. Renewed November 26, 1924.

To all whom it may concern:

Be it known that I, EDWARD A. RUSSELL, a citizen of the United States, residing at Chicago, in the county of Cook and State of

5 Illinois, have invented certain new and useful Improvements in Automatic Car-Heating Systems, of which the following is a specification.

10 My invention relates to a car heating system which is automatically controlled to maintain a normal living temperature in the car during periods of occupancy, that is, when the car is coupled up with a locomotive or is standing at a terminal station, and 15 to establish and maintain a lower temperature, sufficient to keep water pipes and fixtures from freezing, when the car is cut off from the locomotive and is standing in a railroad yard, for example, with its steam train pipe connected with a stationary 20 source of supply of steam.

25 The system of control contemplated by this invention is specially adapted for a low pressure or "vapor" type of steam heating apparatus employing an automatically governed radiator valve which when closed, that is, when in position to shut off inflow of steam to the radiator, opens a drain port on the radiator side of the valve through 30 which water of condensation may escape from the radiator. A control system of this sort is described in my co-pending application Serial No. 434,179 filed December 31, 1920, and it contemplates having the steam train pipe of the car connected with a source 35 of steam supply in the yard or terminal whenever, during cold weather, the car is cut off from the locomotive. It may happen, however, that the car when taken to the 40 yard is not connected up with the steam supply pipe and when such is the case, if the valve happens to be left open so that its drain pipe is closed (which will depend upon the car temperature at the time the 45 car is cut off) or if the valve, though closed at the time, is subsequently opened, automatically, through operation of the control mechanism, opportunity will be given for water to trap in the valve and freeze. To 50 avoid this my present invention provides a

device which operates automatically, in such contingencies, to move the valve from its open to its closed and draining position.

In the drawing,

Fig. 1 is a diagrammatic view of the heating system as a whole, the radiator valve being shown in the open position. 55

Fig. 2 is a detail view of the radiator valve showing the same in closed position, 60 and

Fig. 3 is a view, on a larger scale, illustrating the thermostatic attachment on the steam train pipe for closing the radiator valve in the contingencies before mentioned. 65

Referring to the drawing, A designates the steam train pipe of a railway car provided with a radiator which is shown as consisting of two pipe coils B and C. D is a four-way valve for controlling the flow of steam through the radiator, and E and F are motors for closing and opening the valve. G is a vapor regulator, so-called, for reducing inflow of steam to the radiator in accordance with the temperature of the medium outflowing therefrom, this device being of common construction and requiring no detailed description. H is a limit switch for breaking the circuits through motors E and F as soon as the valve has been moved from one position to the other. 70 J is a relay, the position of the armature of which determines whether motor E or motor F is energized under certain operating conditions. K is a thermostat located in the car which is put into control of the system, when the car is disconnected from the locomotive, to maintain the car atmosphere at a relatively low temperature, for example, 50° Fahrenheit. L is a similar thermostat which is put into control of the system 75 when the car is connected with the locomotive to maintain the car atmosphere at a normal living temperature, say 70° Fahrenheit. M is a selector switch for determining whether the heating system shall be controlled by low temperature thermostat K or high temperature thermostat L, the switch M being, in effect, an air and spring motor, the moving part of which is moved in one direction by air pressure derived 80

from the air brake or signal train line, that is to say, switch M is actuated through air pressure in one of the air train lines when the car is operatively connected with the locomotive to put the high temperature thermostat L in control of the heating system. When air disappears from the train line, as will happen when the car is cut off from the locomotive, selector switch M operates automatically to put the low temperature thermostat K in control of the system. The selector switch can be manually set to the high temperature position, when there is no air pressure in the air train line, so that the car may be heated to normal temperature when it is standing in a terminal station. N is a master switch for disabling the entire control system. Q designates the battery or other source of supply of current, and R a circuit breaker arranged on the train pipe K which, through the cooling of the train pipe incident to the disconnection of the car from the locomotive, operates to bring about the closing of the radiator valve or to prevent said valve, if closed, at the time the car is cut off from the train, from being subsequently opened, if it happens that the steam train pipe of the car, instead of being connected with a stationary yard or terminal steam line, is left unsupplied with steam. The closing of the valve involves, as stated above, the opening of a drain port on the radiator side of the valve through which water of condensation in the radiator may outflow instead of being trapped in the valve.

Operation: The parts of the apparatus, as shown in Fig. 1, are in the positions which they assume when the car is cut off from the locomotive but supplied with steam from the yard or terminal steam line and with the car temperature below that at which low temperature thermostat K, now in control of the system, is set to function, that is to say, the car temperature is below 50° Fahrenheit. The steam train line A is hot and thermostat R associated therewith is expanded to break the circuit which it controls. The relay J is energized to raise its armature 10 by a circuit as follows:

Circuit No. 1. Wire 11 from battery Q, arm 12 of switch N, wire 13, resistance 14, relay J, wire 15, arm 16 of switch N, and wire 17 to battery Q.

55 Valve D is open and steam flows through the radiator and its connections as follows: Steam train line A, pipe 18, pressure reducing valve 19 of the vapor regulator G, pipe 20, chamber 21 of radiator valve D, duct 22 of the rotatable valve member 23 of valve D, chamber 24 of the valve, inlet pipe 25 of primary coil B, return pipe 26 of coil B, inlet pipe 27 of coil C, return pipe 28 of coil C, chamber 29, duct 30 and chamber 31 of valve D, and pipe 32 to the thermostat

chamber 33 of vapor regulator G. The water of condensation from coil B instead of being driven around with the steam through coil C, passes from pipe 26 into valve chamber 34 and through a water seal 70 duct 35 to chamber 31 and through pipe 32 to the thermostat chamber 33 of the vapor regulator.

When the temperature of the car reaches the temperature for which low temperature thermostat K is set, that is to say, when the mercury column 36 of thermostat K touches contact 37, a circuit is closed through thermostat K which diverts enough current from the circuit containing relay J and resistance 14 (circuit No. 1) so that the relay J drops its armature 10, thereby closing a circuit through motor F to cause the motor to close valve D. The circuit through the low temperature thermostat K is as follows:

Circuit No. 2. Circuit No. 1 to binding post 38, wire 39, mercury column 36 of thermostat K, contact 37, wire 40, spring contact 41 of the selector switch M, contact plate 42 on the movable member 43 of selector switch M, spring contact 44, wire 45 to wire 15 and thence, as in circuit No. 1, to the battery.

55 Armature 10 of relay J falls on the contacts 46, 47, closing the aforementioned circuit through motor F, as follows:

Circuit No. 3. Circuit No. 1 to binding post 48, wire 49, wire 50, solenoid coil 51 of motor F, wire 52, spring contact 53 of the limit switch H, contact plate 54 of the limit switch member 55, contact spring 56, wire 57, contact 46, armature 10 of relay J, contact 47, wire 58 to wire 15, and thence by circuit No. 1 to the battery.

Motor F is actuated to close valve D, the core 59 of the motor being engaged at 60 with a lever 61 on the rotatable valve member 23 of valve D. Fig. 2 shows the closed position of valve D. Steam from pipe 20 passes directly from valve chamber 21 to 110 valve chamber 31 and to the thermostat chamber 33 of the vapor regulator G through pipe 32, short circuiting the radiator coils B and C. The radiator pipes 25, 26 and 28 of the coils drain through valve 115 chambers 24, 34 and 29, all of which are in communication with valve chamber 62 from which leads a drain pipe 63. Switch member 55 of the limit switch H is engaged by an arm 64 on the valve member 23 so that the closing of the valve by moving the switch member 55 to the right (Fig. 1) so as to bring the insulating block 65 of switch member 55 between spring contacts 53 and 56 breaks the circuit through motor F (circuit No. 3) at this point, deenergizing the motor.

If the temperature should fall below 50° Fahrenheit circuit No. 2 will be broken at the low temperature thermostat and as a 130

consequence of this relay J will be energized to attract its armature 10 (circuit No. 1) so as to bring the armature 10 against contacts 66, 67, closing a circuit through the 5 motor E as follows:

Circuit No. 4. Circuit No. 3 to binding post 68 (between wires 49 and 50), wire 69, coil 70 of motor E, wire 71, spring contact 72, of limit switch H, contact plate 73 of 10 the limit switch member 55, spring contact 74, wire 75, contact 66, armature 10 of the relay J, contact 67, wire 58 to wire 15, and thence by circuit No. 1 to the battery.

The arrangement of the momentary circuit just described through motor E restores the parts of the apparatus to the positions shown in Fig. 1. Valve D is opened, the limit switch H thereupon breaking the circuit through motor E by interposing between spring contacts 72, 74 the insulating block 76 on limit switch member 55.

It will now be assumed that the car is operatively coupled with a locomotive so that air under pressure is conducted from 25 the air train line of the train (the signal line or air brake train line) through pipe 77 to the cylinder 78 of the selector switch M. The movable member 43 of the selector switch is moved to the left (Fig. 1) so that 30 spring contacts 41, 44 are separated by the insulating block 79. This puts the low temperature thermostat out of control by breaking its circuit (circuit No. 2) at the selector switch. Assuming that the car temperature is below that to which the high temperature thermostat L is set, 70° Fahrenheit, for example, the parts of the control apparatus, except for the selector switch, will remain as shown in Fig. 1, that is to say, relay J 35 will be energized and valve D open. The car temperature will be raised to the normal temperature of occupancy, 70° Fahrenheit, whereupon the mercury column 80 of high temperature thermostat L will reach contact 40 81, closing a circuit through the high temperature thermostat L and deenergizing relay J. The circuit through the high temperature thermostat L is as follows:

Circuit No. 5. Circuit No. 2 through 50 wire 39 to mercury column 80 of thermostat L, contact 81, wire 82, wire 45 to wire 15, and thence as in circuits No. 1 and No. 2 to the battery.

Relay J is deenergized, dropping its armature 10 to contacts 46, 47 and a momentary circuit is thereby established through motor F (circuit No. 3) to close the valve D. If the temperature thereafter falls below 70° Fahrenheit the circuit through thermostat L (circuit No. 5) is broken at the 60 thermostat, relay J is energized, and a momentary circuit established through the motor E (circuit No. 4) to re-open the valve.

When the car is cut off from the locomotive and is standing, for example, at a ter-

70 minal with the steam train line connected with a steam supply pipe, the high temperature thermostat may be put in control of the system by manual operation of the selector switch M. This enables the car to be heated to the temperature of occupancy before the locomotive is attached to the train. The movable member 43 of the selector switch for the low temperature control is held against a spring stop 83 by a spring 84 75 backed up against a stationary abutment 85. By releasing the spring stop 83 the switch member will move to the right against the head of cylinder 78 inserting an insulating block 86 between the spring contacts 41, 44. 80 The low temperature thermostat K is thus disabled by the breaking of its circuit (circuit No. 2) at this point. The spring stop 83 bears upon the top of the outer end of the selector switch member so that as soon as air is introduced into cylinder 78 incident to the coupling of the train with the locomotive, the switch member will be moved to its extreme left hand position with 85 spring contacts 41, 44 on the insulating block 79, the spring stop 83 dropping back to its normal position in readiness to re-establish the low temperature thermostat circuit as soon as air pressure disappears from the cylinder 78.

90 I shall next describe the device for insuring the closing of valve D, with the opening of the radiator drain incident thereto, in case the car is cut off from the locomotive steam supply without being connected with a yard or terminal steam supply. In such case, it may be said, the water in the radiator, even if valve D were open, could find an exit, to a certain extent at least, through pipes 20 and 32 (note the scaling 95 duct 35 connecting valve chamber 34 with valve chamber 31) but practical experience has shown that the drainage of the radiator cannot be satisfactorily established, at least in severe weather, with the valve standing 100 in its open position because of the danger of the water freezing in valve D.

105 It will be observed that even if the valve D be closed at the time the car is cut off from the locomotive, the valve will be 110 opened again by the energization of relay J as soon as the car temperature falls low enough to break the circuit through the low temperature thermostat (circuit No. 2). Before this the high temperature thermostat circuit (circuit No. 5) will, of course, 115 have been broken. If the car is put out of service with its temperature between 50° and 70° Fahrenheit, the low temperature thermostat circuit will be closed to deenergize the relay J and bring about a closing of the radiator valve D, but this condition will last only until the car temperature falls below 50° Fahrenheit whereupon valve 120 D will again be opened. In any case, valve 125 D

D will eventually be opened and, quite possibly, this may happen before the radiating coils have completely drained.

To meet this condition the thermostat R 5 is arranged on or adjacent the steam train pipe A. I have shown the thermostat R as consisting of an arc member 87 and a chord member 88 of greater expansibility than the arc member. The thermostat is attached to 10 the pipe in any suitable manner. For example, it may be mounted on a metal block 89, insulation 90 being interposed between the chord member 88 and the block and the block clamped to the pipe A by U bolts 91. 15 92 is the terminal on the chord member and 93 a contact against which the arc member is adapted to bear when the chord member contracts, that is to say, when train pipe A is not under steam and cold. The circuit 20 controlled by thermostat R is, therefore, open whenever the car is receiving steam either from the locomotive or from the yard or terminal steam pipe. It is closed only when the car is not being heated. Assuming 25 that the car is in this condition with valve D open and the selector switch M in the position shown in the drawing, a circuit will be established through thermostat R as follows:

30 Circuit No. 6. Circuit No. 2 to binding post 94 in wire 39 (circuit No. 2 being open at thermostat K) wire 95, contact 93, arc and chord members 87, 88 of thermostat R, binding post 92, wire 96 to binding post 35 97, wire 45, wire 15 and thence following circuit No. 1 to the battery.

The closing of the circuit just described will have the same effect as the closing of 40 the circuit through the low temperature thermostat (circuit No. 2) namely, relay J will be deenergized dropping its armature on contacts 46, 47. This will energize motor F (circuit No. 3) to close valve D. Valve D will remain closed so long as current flows over circuit No. 6, that is to say, 45 so long as pipe A remains cold. As soon as pipe A is heated by introduction of steam thereto circuit No. 6 is broken at 93 and thermostat R is made ineffective and the 50 parts of the controlling apparatus restored either to the positions which they assume with thermostat K in control or the positions which they assume with thermostat L in control, dependent upon the operation of selector switch M.

As it is realized that my invention might be practiced by apparatus differently constructed than that shown and described, I 60 wish it to be understood that the invention includes all modifications of such apparatus within the scope of the appended claims. The term "train pipe" is used to denote any suitable conduit to supply the car heating means with steam.

65 I claim:

1. In a steam heating system for a railway car provided with a steam train pipe, heating means connected with the train pipe to receive steam therefrom, and mechanism comprising a heat sensitive element influenced by the temperature of the train pipe for opening a drainage outlet for water of condensation from the heating means on cessation of steam supply to the train pipe. 70

2. In a steam heating system for a railway car provided with a steam train pipe, heating means connected with the train pipe to receive steam therefrom, and provided with a drainage outlet for water of condensation, and mechanism actuated when the train pipe is supplied with steam to close said outlet and when steam is cut off from the train pipe to open said outlet, which mechanism comprises a heat sensitive element influenced by the temperature of the 80 train pipe. 85

3. In a steam heating system for a railway car provided with a steam train pipe, heating means connected with the train pipe to receive steam therefrom, a valve to close communication between the train pipe and heating means provided with a drainage outlet in communication with the heating means which is open when the valve is closed, and control mechanism for operating said valve comprising a thermostat associated with the train pipe which actuates such controlling mechanism to close said valve and open the drain outlet when steam supply to the train pipe ceases. 90 95

4. In a steam heating system for a railway car provided with a steam train pipe, heating means connected with the train pipe to receive steam therefrom, a valve to close communication between the train pipe and heating means provided with a drainage outlet in communication with the heating means which is open when the valve is closed, a thermostat in the car, and mechanism actuated thereby for opening and closing said 100 valve, and a thermostat associated with the train pipe which on cessation of steam supply to the train pipe effects the closing of said valve. 105 110

5. In a steam heating system for a railway car provided with a steam train pipe, heating means connected with the train pipe to receive steam therefrom, a valve to close communication between the train pipe and heating means provided with a drainage outlet in communication with the heating means which is open when the valve is closed, and mechanism for opening and closing said valve comprising a thermostat in the car which opens the valve at a determined low temperature therein, and a thermostat associated with the train pipe which closes the valve on cessation of steam supply to the train pipe. 115 120 125

6. In a steam heating system for a railway 130

- car provided with a steam train pipe, heating means connected with the train pipe to receive steam therefrom, a valve to close communication between the train pipe and heating means provided with a drainage outlet in communication with the heating means which is open when the valve is closed, and electrically operated mechanism for opening and closing said valve comprising a circuit making and breaking thermostat in the car which breaks a circuit to effect the opening of the valve at a determined low temperature therein, and a circuit making and breaking thermostat associated with the train pipe which makes a circuit and thereby effects the closing of said valve on cessation of steam supply to the train pipe.
7. In a steam heating system for a railway car provided with a steam train pipe, heating means connected with the train pipe to receive steam therefrom, a valve to close communication between the train pipe and heating means provided with a drainage outlet in communication with the heating means which is open when the valve is closed, and electrically operated mechanism for opening and closing said valve comprising a relay which is energized and deenergized to open and close the valve, a circuit making and breaking thermostat in the car which controls a circuit that when made diverts current from the relay circuit to deenergize the relay, and a circuit making and breaking thermostat associated with the train pipe which controls a circuit that when made, diverts current from the relay to deenergize the same.
8. In a steam heating system for a railway car provided with a steam train pipe, heating means connected with the train pipe to receive steam therefrom, a valve to close communication between the train pipe and heating means provided with a drainage outlet in communication with the heating means which is open when the valve is closed, electrically operated mechanism for opening and closing said valve comprising a relay which is energized to open said valve and on deenergization closes the same, a circuit making and breaking thermostat in shunt with the relay which makes its circuit on rise of car temperature, diverting current from the relay, and deenergizing the same, and a circuit making and breaking thermostat associated with the train pipe arranged in shunt with the relay and other thermostat which, in the absence of steam in the train pipe, closes its circuit to deenergize the relay and thereby bring about a closing of the valve.
9. In a steam heating system for a railway car provided with a steam train pipe, a radiator in the car, a valve to open and close communication between the train pipe and radiator, which valve provides a drainage outlet for the radiator that is open when the

valve is in closing position, motors to operate the valve in opposite directions, a relay to control current supply to said motors alternatively, a circuit making and breaking thermostat in the car which controls a circuit that when made diverts current from the relay and deenergizes the same, and a circuit making and breaking thermostat associated with the train pipe controlling a circuit that, when made, diverts current from said relay to deenergize the same.

10. In a steam heating system for a railway car provided with a steam train pipe, a radiator in the car, a valve to open and close communication between the train pipe and radiator, which valve provides a drainage outlet for the radiator that is open when the valve is in closing position, motors to operate the valve in opposite directions, a relay which when energized operates one of said motors to open said valve and when deenergized operates the other motor to close said valve, a circuit making and breaking thermostat in the car in shunt with said relay and controlling a circuit which, when made, deenergizes said relay, and a circuit making and breaking thermostat associated with the train pipe in shunt with the relay and the other thermostat which on cessation of steam supply to the train pipe closes a circuit that deenergizes the relay.

11. In a steam heating system for a railway car, provided with a steam train pipe, a radiator in the car, a valve to open and close communication between the train pipe and radiator, which valve provides a drainage outlet for the radiator that is open when the valve is in closing position, motors to operate the valve in opposite directions, a relay which when energized operates one of said motors to open said valve and when deenergized operates the other motor to close said valve, a low temperature circuit making and breaking thermostat which on rise of car temperature deenergizes the relay, a high temperature circuit making and breaking thermostat functioning at a higher temperature than the first named thermostat, to deenergize said relay, a selector switch by means of which one or the other of said thermostats is put in control of the system, and a circuit making and breaking thermostat associated with said train pipe for deenergizing the relay on cessation of steam supply to the train pipe.

12. In a steam heating system for a railway car provided with a steam train pipe, heating means connected with the train pipe to receive steam therefrom, a valve to control the flow of steam to the heating means which when in closing position provides an outlet for water of condensation from the heating means, and controlling mechanism for said valve comprising a thermostat in the car, functioning on rise of temperature

to a relatively low point to close the valve, a thermostat functioning at a higher car temperature to close said valve, means whereby one or the other of said thermostats may be put in control of the system, and means actuated on cessation of steam supply to the train pipe for effecting the closing of said valve.

13. In a steam heating system for a rail-way car provided with a steam train pipe, heating means, a valve to control the flow of steam to said heating means which in closing position provides an outlet for water of condensation from the heating means, and controlling means for operating said valve comprising two thermostats for effecting the closing of the valve, one of which is located in the car and functions on rise of the car temperature, and the other

of which is associated with the steam train pipe and functions on cessation of steam supply to said train pipe.

14. In a steam heating system for a rail-way car, the combination of a steam train pipe, a radiator in the car, a valve to control communication between the train pipe and radiator having a drainage outlet which is open when the valve is in position to close communication between the radiator and train pipe, an electric circuit breaking thermostat to govern the movements of said valve, and an electric circuit breaking thermostat influenced by the temperature of the train pipe and arranged to close its circuit when the train pipe is cold to short circuit the first named thermostat and to break its circuit when the train pipe is under steam.

EDWARD A. RUSSELL.
